Primary Examiner — Susan E Krakower*(74) Attorney, Agent, or Firm* — Myers Wolin, LLC**(57) CLAIM**

We claim the ornamental design for a sealable pourer, as shown and described.

DESCRIPTION

FIG. 1 is a left rear isometric view of one embodiment of a sealable pourer showing our new design;

FIG. 2 is a left side elevation view thereof, the right side elevation being identical;

FIG. 3 is a front elevation view thereof;

FIG. 4 is a rear elevation view thereof;

FIG. 5 is a cross-sectional view taken along line 5-5 in FIG. 4;

FIG. 6 is a top view thereof; and,

FIG. 7 is a bottom view thereof.
